FOREIGN PATENT DOCUMENTS

EM 001911983 2/2011

Primary Examiner — Freda S Nunn

(74) Attorney, Agent, or Firm — Banner & Witcoff, Ltd.

CLAIM

The ornamental design for an input device for an electronic tablet, as shown and described.

DESCRIPTION

FIG. 1 is a top isometric view of an input device for an electronic tablet showing our new design;

FIG. 2 is a top view thereof;

FIG. 3 is a left side view thereof;

FIG. 4 is a right side view thereof;

FIG. 5 is a rear view thereof; and,

FIG. 6 is a front view thereof.

The broken line showing of various features on the input device for an electronic tablet in FIGS. 1-6 are for environmental purposes only and form no part of the claimed design.
